UNITED STATES PATENT OFFICE.

WILLIS F. WALKER, OF CHARLESTOWN, WEST VIRGINIA.

CONSTRUCTION OF WALLS AND PARTITIONS FOR BUILDINGS OR OTHER STRUCTURES.

SPECIFICATION forming part of Letters Patent No. 727,234, dated May 5, 1903.

Application filed September 30, 1902. Serial No. 125,433. (No model.)

To all whom it may concern:

Be it known that I, WILLIS F. WALKER, a citizen of the United States, residing at Charlestown, in the county of Jefferson and State of West Virginia, have invented a new and useful Construction of Walls and Partitions for Buildings or other Structures, of which the following is a specification.

This invention relates to the construction of walls and partitions for buildings and other structures.

The object of the invention is in a ready, cheap, thoroughly feasible, and practical manner to facilitate the work of building walls, partitions, &c., and to protect the metal employed in the construction from corrosion and fire.

With these and other objects in view, as will appear as the nature of the invention is better understood, the same consists in the novel construction and combination of parts of a composite slab to be used in the construction of walls, partitions, and the like, as will be hereinafter fully described and claimed.

In the accompanying drawings, forming a part of this specification, and in which like numerals of reference indicate corresponding parts, there are illustrated two forms of embodiment of the invention capable of carrying the same into practical operation, it being understood that the elements therein exhibited may be varied or changed as to shape, proportion, and exact manner of assemblage without departing from the spirit thereof, and in these drawings—

Figure 1 is a view in perspective, partly broken away to show the interior arrangement of a slab or section constructed in accordance with the present invention. Fig. 2 is a perspective view of a completed slab. Figs. 3 and 4 are views in sectional plan, exhibiting two different ways by which the frame-irons may be held assembled.

In carrying the invention into effect a plurality of I-beams 1, of any desired length, are taken and secured in parallel relation to each other by brace-bands or tie-bars 2, which may be disposed between the webs of the beams either by angle-bends, as shown in Fig. 3, or curved bends, as shown in Fig. 4, the object of either arrangement being to effect alternate

securement of a brace to pairs of parallel-disposed beams, thus to permit of requisite expansion and contraction of the structure as a whole. The flanges of the beams on both sides thereof are preferably of the same width—that is to say, are each to project laterally the same distance beyond the web and are to be disposed sufficiently close to each other as to effect proper tying or anchoring of the cement, concrete, or other plastic material constituting the filling or facing of the slabs or sections. The two outer beams 3 of each section are channel or half-I beams, thereby to present the requisite flat surfaces to permit of the sections being firmly superposed in the building of a wall, partition, or the like.

When the beams have been associated in parallel relation with each other, either in the manner shown or otherwise, a filling 4, of any plastic material suited to the purpose, is placed between the opposed flanges of the beams and projects laterally beyond the same, thus wholly investing the metal framework and covering the flanges at opposite sides thereof to effect its protection, as from corrosion or fire. Both sides of the slab being finished at the factory, when they are set up in position no further work will be required other than to point the seams between the meeting edges of the sections.

The advantage of employing a structure such as described in the building of walls and the like is that when furnished to the builder they are dry, and may thus be immediately set up, thus saving time that is usually lost in waiting for ordinary plaster to dry, especially when applied to partitions before the finished coating of plaster-of-paris may be applied thereto. Furthermore, the construction of the wall or the like will be largely expedited, inasmuch as each slab will contain an area equal to a large number of bricks. Excessive care in building a wall will also be obviated for the reason that the slab will be a finished product when received and will be mathematically correct as to the lines of its operative faces.

Having thus fully described my invention, what I claim as new, and desire to secure by Letters Patent, is—

1. A composite slab for building purposes

comprising members having webs and flanges at opposite edges of the webs, braces alternately attached to the webs of opposite members, and a filling interposed between and covering the opposite flanges of the members and embedding the braces.

2. A composite slab for building purposes, comprising a frame composed of a plurality of rigidly-spaced I-beams and lateral half-I beams, the flanges of which project inward, and a filling interposed between the webs of the beams and covering the flanges thereof.

3. A composite slab for building purposes comprising a frame composed of rigidly-connected I-beams, the flanges of which are dis-

posed in the same plane and project like distances beyond the webs on both sides of the beam, half-beams constituting the sides of the slab and having their flanges projected inward, and a filling interposed between the webs and beams and covering the flanges thereof.

In testimony that I claim the foregoing as my own I have hereto affixed my signature in the presence of two witnesses.

WILLIS F. WALKER.
